UNITED STATES PATENT OFFICE.

MERRICK A. MIHILLS, OF CHICAGO, ILLINOIS.

RAZOR-STROP.

970,939.

Specification of Letters Patent. Patented Sept. 20, 1910.

Application filed February 25, 1910. Serial No. 545,908.

To all whom it may concern:

Be it known that I, MERRICK A. MIHILLS, a citizen of the United States of America, residing at Chicago, in the county of Cook 5 and State of Illinois, have invented new and useful Improvements in Razor-Strops, of which the following is a specification.

This invention relates to razor strops, and it has for an object to provide a strop having a honing surface and a finishing surface and to provide a cleaning strop supported by the honing strop and mounted thereto so that in use of the honing strop the said cleaning strop may be swung so that 15 its main body portion will hang downwardly at one side of the honing strop and out of the way of the hands of the operator.

A still further object of my invention is to so assemble the two strops that the one 20 forming the cleaning surface can be readily removed from the one forming the honing and finishing surfaces so that it can be used independently thereof if desired.

In the drawing, forming a portion of this 25 specification and in which like numerals of reference indicate similar parts in the several views:—Figure 1 is a detail perspective view of my improved device showing the honing surface of the honing strop exposed for use and showing the cleaning strop swung so that its main body portion lies downwardly at one side of the honing strop. Fig. 2 is a detail transverse section 30 through the two strops showing the manner 35 of connecting them together.

The device consists preferably of a strop 1 having a honing surface 2 and a finishing surface 3. At one end the strop is provided with a handle member 4 and at the 40 opposite end the strop has secured thereto a leather member or the equivalent thereof in which is formed a loop for receiving one arm of a yoke 5. This yoke is provided with a swivel eye member 6 which may be 45 engaged with a hook or any other equivalent suspending means. A perforation 7 is formed in the strop 1 and as shown, this 50 perforation receives the threaded portion of a bolt 8 on which is formed an annular shoulder 9 and a head 10. A retaining member 11 is formed to provide a main body 55 portion 12 which has formed therein intermediate of its ends a passage 13 for receiving the shoulder 9 of the bolt. The head 10 is disposed at one side of the main body portion 11 of the retaining member and it is

held thereto through the provision of a clamping nut 14 which is engaged with the threaded portion of the bolt and adjustable thereon so that it can be moved against the 60 strop 1 as shown in Fig. 2 of the drawing. The main body portion of the retaining member has its terminals bent outwardly and then inwardly toward each other to form arms 15. These arms 15 are suitably 65 spaced from the main body portion of the retaining member so that the upper end portion of a cleaning strop 16 can be positioned between the main body portion of the retaining member and the arms 15 thereof. The 70 strop 16 is provided at its upper end with a stop member 17 which is formed so that it will engage the main body portion and the arms 15 respectively of the retaining member 75 to limit the movement in one direction of the cleaning strop and to hold it effectively against displacement from the retaining member. The stop member 17 is formed to provide an eye 18 so that should the operator desire to remove the cleaning 80 strop from the honing strop such can be readily accomplished and the eye of the cleaning strop may be engaged with any suitable supporting hook. The opposing or 85 spaced terminal ends of the retaining member are curved outwardly as shown, to facilitate the insertion of the cleaning strop between the main body portion and the arms 15 respectively of the retaining member. 90

In use, when it is desired to hone the 90 razor the handle portion 4 of the strop 1 is held in one hand of the operator and with the other hand, the operator may move the retaining member so that it assumes the position approximately at right angles to the strop 1. In this position of the retaining member the cleaning strop will hang downwardly from the holding strop as shown in Fig. 1 of the drawing and the user can conveniently manipulate the razor on the honing surface of the strop 1 without the cleaning strop obstructing the path. 100

I claim:—

1. In a device of the class described, a 105 honing and finishing strop, a cleaning strop, and a member pivotally engaged with one of such strops and having retaining means with an open portion for receiving and supporting such strop, the said means being 110 mounted for pivotal movement whereby it may be swung to assume a position approximately at right angles to the said honing

and finishing strop so that the cleaning strop may be moved to a position to hang downwardly at one side of the said honing and finishing strop and over one edge of the same.

2. In a device of the class described, companion strops, a bolt extending through one of the strops, an annular shoulder formed upon the bolt, and a retaining member apertured to receive the shoulder of the said bolt, the said retaining member being formed to provide a support for one of the strops and provided with spaced arms overlying such strop.
- 10 3. A device of the class described comprising companion strops, a bolt extending through one of the strops, a retaining mem-

ber supporting the other strop and mounted for pivotal movement on the bolt, the said retaining member having a main body portion extending transversely of its supported strop, and arms spaced from the said main body portion and connected therewith and spaced from each other at their opposing or terminal ends to facilitate the engagement of the strop with the said retaining member.

In testimony whereof I affix my signature in presence of two witnesses.

MERRICK A. MIHILLS.
